UNITED STATES PATENT OFFICE.

JAMES HIRST, OF OTTUMWA, IOWA.

AXLE-SETTING TOOL.

1,233,271.

Specification of Letters Patent. Patented July 10, 1917.

Application filed July 6, 1915. Serial No. 38,370.

To all whom it may concern:

Be it known that I, JAMES HIRST, a citizen of the United States of America, and resident of Ottumwa, in the county of Wapello and State of Iowa, have invented a new and useful Axle-Setting Tool, of which the following is a specification.

The object of this invention is to provide means for determining the taper of an axle 10 and gaging the spring of an axle so as to give the desired dish and gather of wheels supporting said axle.

A further object of this invention is to provide means for determining the degree 15 of inclination and forward direction to be given to spindles to provide for the dish and gather of wheels.

A further object of this invention is to provide means of gaging and determining the 20 amount of spring and flexing to give a metal axle in order that wheels carrying said axle may have the proper degree of gather and dish.

My invention consists in the construction, 25 arrangement and combination of elements hereinafter set forth, pointed out in my claims and illustrated by the accompanying drawing, in which—

Figure 1 is a plan illustrating the use of 30 my device in gaging the gather of the spindles on a steel axle. Fig. 2 is a side view of the device. Fig. 3 is an elevation illustrating the use of my device in gaging the inclination of spindles of a wooden 35 axle, one spindle carrying a skein. Fig. 4 is a front elevation and Fig. 5 is a plan of a caliper and adjusting tool employed in adjusting the setting tool.

In the construction of the tool as shown 40 the numeral 10 designates a gage bar, preferably made of metal and of uniform width and thickness throughout its length. The gage bar 10 is formed with a cross-head on one end forming arms 11, 12, which arms 45 are provided with contact blades 13 on their outer ends, the longest dimension of said blades being at right angles to and crossing the width of the arms. A cross-head 14 is mounted slidingly on the gage bar 10 and 50 is adapted to be secured to said bar by a set-screw 15. The cross-head 14 is provided with contact blades 13^a on its ends and integral therewith. Further contact blades 13^b are mounted on the end portions of the 55 cross-head 14 and are adjustable to project beyond the blades 13^a when desired and are

secured in any desired adjustment by set-screws 16. The cross-heads on the gage-bar 10 are adapted to be spaced apart approximately the length of an axle 17, so that in use blades 13, 13^a or 13^b may contact with the spindles 18, 19 adjacent to shoulders 20, 21 of said axle. Hence the advantage of adjustable mounting of the cross-head 14 on the bar 10. A bolt or rivet 22 is mounted through the central portion of the fixed cross-head between the arms 11, 12 and a dish-gage bar 23 and a gather-gage bar 24 are arranged parallel with and above and below the bar 10 respectively and are pivoted between their ends on said bolt. A scale plate 25 is mounted on and transversely of the gage bar 10 between the cross-heads and is graduated on both its long margins on its outer face. The inner end portion of the dish-gage bar 23 is attenuated to form a pointer or indicator 26 which is directed toward and adjacent to one graduated margin of the plate 25. A boss 27 is formed in the bar 23 adjacent to the indicator 26 and a slot 28 is formed in said boss and bar and extends transversely of the bar. A set-screw 29 is mounted loosely through the slot 28 and is screwed into the gage-bar 10. A collar 30 is mounted slidingly and non-rotatably on the outer end portion of the dish-gage bar 23 and is adapted to be secured in any desired adjustment longitudinally of said bar by a set-screw 31. A gage-arm 32 is mounted slidingly and non-rotatably in the 80 collar 30 and extends transversely of the bar 23 and to one side thereof. The arm 32 is formed with a contact blade 33 on its outer end alining at times with blades 13 and 13^a on the same side of the gage-bar 10. The arm 32 is secured in any desired adjustment in the collar 30 by a set screw 34. The gather-gage bar 24 is formed with a hook 35 on its inner end, which hook extends over the gage-bar 10 and is formed 90 with a slot 36 transversely of the latter bar, and also is formed with a pointer or indicator 37 directed toward and adjacent to a graduated margin of the plate 25 opposite to the indicator 26. A set-screw 38 is mounted loosely through the slot 36 and is screwed into the gage-bar 10. A collar 39 is mounted slidingly and non-rotatably on the outer end portion of the gather-gage bar 24 and is adapted to be secured in any 100 desired adjustment longitudinally of said bar by a set-screw 40. A gage-arm 41 is

mounted slidably and non-rotatably in the collar 39 and extends transversely of the bar 24 in a direction opposite to that of the arm 32. The arm 41 is formed with a contact blade 42 on its outer end alining at times with blades 13 and 13^a on the same side of the gage-bar 10. The arm 41 is secured in any desired adjustment in the collar 39 by a set-screw 43. The collars 30 and 39 are in superposed relations when the tool is in the horizontal position shown in Fig. 2. The arms 11 and 12 may be offset or sprung laterally in opposite directions to bring the blades 13 into alinement with other contact blades.

The caliper and adjusting tool is constructed as follows:

A stem 44 is formed with an arm 45 on and projecting laterally from its central portion. A yoke 46 is fixed to the outer end of the arm 45 and is adapted to rest on and embrace the outer ends of the bars 23, 24 at times and support the caliper and adjusting tool on the setting devices. Bearings 47, 48 are mounted rigidly on and project laterally from the end portions of the stem 44 and have their seats registering on a plane parallel with the trend of said stem. An adjusting screw 49, having opposite threads 50, 51 on opposite sides of its center, is journaled loosely in the seats of the bearings 47, 48. The screw 49 is provided with a circumferential flange 52 formed or rigidly fixed on its central portion and said flange is adapted to rotate in a guide 53 on the arm 45. The screw 49 is provided with means for turning it, such as a handle 54 at one end and an angular shank 55^a at the opposite end. Cross-heads 55, 56 are mounted loosely on the stem 44 on opposite sides of the arm 45, and portions of said cross-heads are formed with oppositely-threaded screw-seats adapted to receive the screw 49 and engage the threads 50, 51 respectively and, continuing beyond said screw, said portions are finished as parallel caliper arms 57, 58. Arms 59, 60, of the cross-heads 55, 56 opposite to the screw 49, are offset and extend outwardly from the trend of the cross-heads and terminate in stems 61, 62 parallel with the stem 44 and screw 49. Links 63, 64 are formed with slide bearings 65, 66 on their outer ends and at right angles thereto, and said bearings are slidably and nonrotatably mounted on the stems 61, 62 and are adapted to be secured in any desired adjustment thereon by means of set-screws 67, 68. Yokes 69, 70 are formed on and project laterally from inner end portions of the links 63, 64 and are adapted to embrace, at times, and be secured by set-screws 71, 72 to the arms 32 and 41 respectively on the setting tool.

In the practical use of this tool, in respect of a metal axle 17, to determine the gather

and dish of the spindles, the operation is as follows: The cross-head 14 is adjusted on the gage-bar 10 so that the blades 13, 13^a are spaced to engage the spindles 18, 19 adjacent to the shoulders 20, 21. Normally, when not in use, the pointers 26, 37 rest at 0 on the scale bar 25, the bars 10, 23, 24 lie parallel with each other and in register transversely, and the relative lengths of the arms of the cross-head 14, arms 11 and 12 and gage arms 32 and 41 are such that the extremities thereof lie in common planes parallel with the median longitudinal line of said bars. Manipulation hereinafter described to ascertain the dish and gather of spindles on the axle depends on a rearrangement of the extremities of the cross-head 14, arms 11 and 12 and gage arms 32 and 41 which removes them from the common planes above mentioned. The caliper arms 23 are spaced, by manual rotation of the adjusting screw 49, to the diameter of the tip end of either spindle 18, 19. Then the caliper and adjusting tool is arranged with the yoke 46 on and engaging the bars 23, 24 as shown in Fig. 5; the indicators 26 and 37 being on the centers of the graduated scales of the plate 25 and secured by tightening of the set-screws 29 and 38. The arms 32 and 41 are moved inward in the collars 30 and 39 as far as they will move and are secured temporarily by tightening of the set-screws 34 and 43. The collars 30 and 39 are adjusted on the bars 23 and 24 so as to be spaced from the cross-head arms 11, 12 a distance approximating to the length of the tapering portion of either spindle 18, 19 and secured by tightening the set-screws 31 and 40. The set-screws 67, 68 are tightened and the yokes 69, 70 are caused to embrace the arms 32 and 41, respectively, and the set screws 71, 72 are tightened. Then the set screws 34 and 43 are loosened and the caliper is expanded by manual rotation of the adjusting screw 49 until said caliper measures (through the use of the arms 57, 58) the diameter of the spindle adjacent to the shoulder; the entire tool being handled and manipulated to cause the caliper to embrace the spindle while the axle is supported as on a bench or forge and anvil in a shop, or the axle being manipulated and handled while the tool is supported in a suitable like or similar manner. Expansion of the caliper to the degree described, results in withdrawing the arms 32 and 41 from the collars 30 and 39 equal distances identical with the difference in radius of the ends of the tapered portion of either spindle. Then the set screws 34 and 43 are tightened; the set-screws 71 and 72 are loosened and the caliper and adjusting tool is removed from the bars 23, 24. Then the gather-gage bar 24 is oscillated on the bolt 22, the set-screw 38 being first loosened, to the degree desired by the operator.

ator as for instance $\frac{1}{16}$ inch as shown on scale, and said set-screw is tightened. Then the dish of the wheel to be used is measured, the set screw 29 is loosened, the dish-gage 5 bar 23 is oscillated on the bolt 22 the degree desired by the operator as for instance two inches as shown on the scale, and then the set-screw 29 is tightened. Then the tool is applied to the front of the axle 17 as 10 shown in Fig. 1 and the spindles are sprung just inside the shoulders 20, 21 until the degree of spring is determined by engagement of the blades 13 and 42 on the arms 11 and 41 respectively as shown in Fig. 1, thus 15 determining the degree of gather of the spindles on the axle. The tool is used first on one spindle and then reversed and used on the other spindle. Then the tool is applied to the top of the axle and the spindles 20 are sprung or bent downward just inside the shoulders until the degree of spring downward is determined by engagement of the blades 13 and 33 on the arms 12 and 32 respectively as indicated in a general way in 25 Fig. 3, thus determining the degree of dish of the spindles on the axle. It is to be understood that this tool does not bend or 30 spring the axle or spindles, but gages and determines the degree to which said bending is to be done and ascertains when it is accurately done.

When a wooden axle 17^a is treated, it is not bent; but the spindles or axle-arms, such as 19", are shaved and reduced to the desired 35 taper on lines determined by the use of the tool as above described, and particularly in respect of the use of skeins 18^a. When said skein is used, to determine its angularity properly, a contact plate 13^b on each arm 40 of the cross-head 14 is extended a distance equal to the thickness of the skein and secured by the set-screw 16 (Fig. 3). This compensates for the thickness of the skein in using the tool to set the first skein; then 45 the plates 13^b are loosened and withdrawn before setting the second skein; the first skein remaining on its spindle during the operation of setting the second skein which is gaged by using the contact plate 13^a.

50 It is to be understood the adjustment of the dish-gage bar 23, in respect of angularity to the bar 10 is determined by measuring the dish of the wheel to be used in each spindle; and the adjustment of the gather-gage bar 24 in like manner is determined by 55 the mechanic using the tool or the specifications governing the work in hand.

I claim as my invention—

1. An axle-setting tool comprising a gage-

bar having a fixed cross-head on one end 60 and an adjustable cross-head on the other end, dish-gaging and gather-gaging bars pivoted on the first bar coincident with the fixed cross-head, coacting indicator devices on said bars, collars adjustably mounted on 65 said latter bars, arms adjustably mounted in said collars, and means for adjusting said arms.

2. In an axle-setting tool, a gage bar, a cross-head fixed thereto, a cross-head mounted on and adjustable longitudinally of the gage bar in opposition to the fixed cross-head, contact plates on end portions of said adjustable cross-head, auxiliary contact plates on and adjustable longitudinally of 75 said adjustable cross-head and adapted to project beyond the first contact plates at times, dish-gaging and gather-gaging bars pivoted on the first bar, interacting scales and pointers on said bars, collars mounted 80 for longitudinal adjustment on end portions of the dish-gaging and gather-gaging bars opposite to the pointers thereof, and cross-arms mounted for adjustment transversely of and carried by said collars. 85

3. In an axle-setting tool, a gage bar, a cross-head fixed thereto, a cross-head mounted on and adjustable longitudinally of the gage bar in opposition to the fixed cross-head, dish-gaging and gather-gaging bars 90 pivoted on the first bar, interacting scale and pointers on said bars, collars mounted for longitudinal adjustment on end portions of the dish-gaging and gather-gaging bars opposite to the pointers thereof, and cross-arms mounted for adjustment transversely 95 of and carried by said collars.

4. The combination of an axle-setting tool and a caliper and adjusting tool comprising a stem adapted for mounting on an axle, 100 caliper arms mounted loosely on the stem, an adjusting screw journaled to the stem and threaded to the caliper arms oppositely, and links adapted to connect the caliper arms to gage arms of the axle-setting tool. 105

5. In a tool of the class described, a stem, bearings thereon, caliper arms on the stem, a guide on the stem, an adjusting screw loosely journaled in the bearings and threaded through the caliper arms oppositely, a 110 flange on said screw engaging said guide, links on said arms, and engaging means on said links.

JAMES HIRST.
